ABSTRACT OF THE DISCLOSURE

Cleaner for fabrics containing soap, glycerin and sodium thiosulfate.

CROSS REFERENCE TO RELATED APPLICATION

This application is a continuation-in-part of my pending application Ser. No. 168,361 filed Aug. 2, 1971 now abandoned.

BACKGROUND OF THE INVENTION**Field of the invention**

This invention is in the field of aqueous based cleaners containing soap and other additives.

Description of the prior art

While aqueous cleaners based upon soap are old in the art, the present invention provides improved cleaning ability by the inclusion of glycerin and sodium thiosulfate.

SUMMARY OF THE INVENTION

The present invention is directed to a cleaner containing an aqueous base and soap, glycerin and sodium thiosulfate.

DESCRIPTION OF THE PREFERRED EMBODIMENTS

The cleaner of the present invention is produced as follows. In making one gallon of the cleaner, from four to twelve ounces of soap flakes are added to one gallon of water and the solution is boiled until the soap flakes are dissolved. The resulting soap solution is then removed from the source of heat and from one to two fluid ounces (two to four tablespoonfuls) of glycerin are added while the soap solution is still very hot. After stirring for about three minutes, from four to twelve ounces of sodium thiosulfate are added and the mixture is stirred again. When the composition cools, it is a snow-white cleaner which can safely be used on any kind of fabric without leaving

5

a stain or fading the colors. It is capable of removing paint, grease, ink and all common stains.

A particularly preferred formula of my invention was prepared as follows:

Example

Eight ounces of soap flakes were added to one gallon of tap water, and the solution was brought to a boil and held there until the soap all dissolved. After removal of the soap solution from the source of heat, three tablespoonfuls (one and one-half fluid ounces) of glycerin were added to the still hot soap solution. Eight ounces of sodium thiosulfate were added with constant stirring. After cooling, a white gel-type cleaner resulted which had excellent cleaning characteristics on all types of fabrics.

I claim as my invention:

1. A spot remover composition consisting of for every gallon of water, from four to twelve ounces of soap, from one to two fluid ounces of glycerin and from four to twelve ounces of sodium thiosulfate, said composition being in the form of a gel.

2. A spot remover according to claim 1 containing approximately one and one-half fluid ounces of glycerin, and approximately eight ounces of sodium thiosulfate.
